[57] ABSTRACT

A strip accumulator comprises a group of fixed rollers and a group of vertically movable rollers, the fixed and movable rollers being arranged in tiers with the same number of fixed tiers as movable tiers, and a number of return rollers equal to one less than the number of tiers, the strip passes over the rollers of one fixed tier and one movable tier, passing from a roller of one tier to a roller of the other tier, then over a return roller to the next pair of fixed and movable tiers.

FIG. 4

STRIP ACCUMULATOR

This invention relates to a strip accumulator.

In the various stages in the production of metal strips, a continuous operation preceded or followed by an intermittent operation is frequently carried out on the same production line.

To this end, strip accumulators adapted to store a certain strip length are interposed in the production line.

The object of this invention is considerably to increase the strip length capable of being stored in an accumulator, for one and the same accumulator size. To this end, the invention provides a strip accumulator, more particularly for metal strip, comprising two units each consisting of a plurality of rollers in groups, one of the units being fixed in position, and the other unit being movable, wherein each of the units comprises a plurality of tiers of rollers at different levels, the number of tiers being the same for both units, and the fixed unit comprises return rollers in a number equal to one less than the number of tiers of each of the units, whereby a strip passes over all the rollers of the one tier of each unit, passing each time from one roller of one unit to one roller of the other unit and then passes over a return roller before passing over all the rollers of the next tier of each unit.

It will be apparent that the multiplication and appropriate arrangement of the rollers of these two units results in a very much extended development of the length of the strip stored in the accumulator according to the invention, for one and the same accumulator size.

In order that the invention may be more readily understood, a known type of strip accumulator will be described hereinafter, followed by two embodiments of an accumulator according to the invention, which embodiments are given by way of example only, with reference to the accompanying drawings, in which:

FIG. 1 is a vertical section through a strip accumulator of known type,

FIGS. 2 and 3 are vertical sections through two different embodiments of accumulators according to the invention, the frame of the movable rollers being in its lower position, and

FIG. 4 is a vertical section through the embodiment of FIG. 2 but with the movable roller frame in its upper position.

In the known type of accumulator shown in FIG. 1, the strip 1 passes successively over rollers 2 and 3. The axes of the rollers 2 are fixed. The axes of rollers 3 are movable, the rollers 3 being mounted on a frame 4 which is vertically movable.

In the known accumulator shown in FIG. 1, if the frame 4 moves downwardly, the length stored in the accumulator increases, while it decreases if the frame 4

moves upwardly.

The accumulators according to the invention enable the strip storage capacity to be increased considerably for the same size of accumulator.

5 An embodiment of an accumulator according to the invention comprises groups of fixed-position rollers 12 (corresponding to the rollers 2 in the known accumulator) and groups of rollers 13 mounted on a frame 14 adapted to move vertically (corresponding to the rollers 3 in the known accumulator).

10 Reversing rollers 15 at the ends of the accumulator enable the strip 11 to be given the correct path (return to the interior of the accumulator or exit therefrom).

FIG. 2 shows one embodiment of the invention wherein the rollers 12 and 13 are in groups of three. In this case (as is generally the case for groups of odd number), the strip exit is on the opposite side of the accumulator to the strip entry.

15 FIG. 3 shows a second embodiment of the invention wherein the rollers 12 and 13 are in groups of four. In this case the entry and exit of the strip are on the same side of the accumulator (this applies whenever there is an even number of rollers in a group).

20 Finally, FIG. 4 shows the accumulator of FIG. 2 with the frame 14 in its upper position, showing the facility of introduction of the strip 11 into the accumulator in this position of the frame 14, such facility being an additional advantage of these accumulators.

25 Of course variants and improvements as to detail are possible as is the use of equivalent means without departing from the spirit and scope of the invention.

What is claimed is:

1. A strip accumulator, more particularly for metal strip, comprising two units each consisting of a plurality of rollers in groups, one of the units being fixed in position, and the other unit being movable, wherein each of the units comprises a plurality of tiers of rollers at different levels, the number of tiers being the same for both units, and the fixed unit comprises return rollers in a number equal to one less than the number of tiers of each of the units, whereby a strip passes over all the rollers of the one tier of each unit, passing each time from one roller of one unit to one roller of the other unit and then passes over a return roller before passing over all the rollers of the next tier of each unit.

40 2 A strip accumulator according to claim 1, wherein the number of tiers of each of the units is odd, the number of return rollers being even, whereby the strip enters the accumulator at one side thereof and leaves on the other side.

45 3. A strip accumulator according to claim 1, wherein the number of tiers of each of the units is even, the number of return rollers being odd, whereby the strip enters the accumulator on one side thereof and leaves on the same side.
